UNITED STATES PATENT OFFICE.

CHARLES H. WHITMAN, OF DES MOINES, IOWA.

TARGET.

1,208,254.

Specification of Letters Patent. Patented Dec. 12, 1916.

Application filed March 7, 1916. Serial No. 82,631.

To all whom it may concern:

Be it known that I, CHARLES H. WHITMAN, a citizen of the United States, and resident of Des Moines, in the county of 5 Polk and State of Iowa, have invented a certain new and useful Target, of which the following is a specification.

The object of my invention is to provide a target of simple, durable and inexpensive 10 construction, adapted for use with air rifles and the like.

A further object is to provide such a target having an alarm, and means for sounding the alarm, said means being so arranged 15 that the shot may be saved and used again.

Still a further object is to provide such a device so constructed that it may be readily taken apart for replacing any of the parts.

20 Still a further object is to provide such a target having a removable perforated bottom member of cheap material which can be quickly and easily replaced.

My invention consists in the construction, 25 arrangement, and combination of the various parts of the device, whereby the objects contemplated are attained, as hereinafter more fully set forth, pointed out in my claims, in which:

30 Figure 1 shows a vertical, central sectional view through a target embodying my invention. Fig. 2 shows a front elevation of the same part of the pasteboard target being broken away, and Fig. 3 shows a front 35 elevation of the pasteboard target.

In the accompanying drawings, I have used the reference numeral 10 to indicate generally a metal cylinder having at its forward end an annular inwardly extending 40 flange 11. Formed in the upper wall of the cylinder 10 is a slot 12 to receive the removable target member 13, which is made of cheap material such as pasteboard which will be readily perforated by the shot from 45 an air rifle, and which is designed to have indicating circles 14, as clearly shown in Figs. 2 and 3.

Mounted within the cylinder 10 and 50 spaced from the flange 11 a suitable distance is a wall or projection member 15. The wall or projection may be made secure to the interior of the cylinder 10 by means of angle brackets 16, screw-bolts 17, and nuts 19, if desired.

55 Supporting members comprising strips 20 resting against the wall of the cylinder 10

and having upwardly extending flanges or members 21 adapted to be secured to the member 15 by means of screw-bolts 17, similar to those already described, may be used 60 for securing the partition 15 to the cylinder.

At the forward ends of the strips 20 are flanges 22 turned radially inwardly within the cylinder and spaced from the flanges 11 a sufficient distance to permit the edge of 65 the target member 13 to be inserted between the flanges 11 and 22.

Received within the cylinder 10 adjacent to the partition or wall member 15 is a comparatively thick disk 23, preferably of felt 70 or some other material suitable for stopping the shot without destroying it.

Angle brackets 24 may be adjustably secured to the cylinder 10 in front of the felt pad 23 for holding the pad in position. 75

Secured to the rear surface of the partition 15 preferably above the central portion thereof is a gong bell 25. Below the gong bell and preferably below the center of the partition 15, two horizontal slits are cut 80 in the partition 15, and a strip 26 between them is bent rearwardly to form a loop. The flat spring member 27 is extended between the loop member 26, and the body of the partition 15, as shown in Fig. 1. At 85 its upper end the spring 27 has a portion 27^a bent at right angles to the body thereof and extending forwardly in the target through a suitable opening in the central part of the partition 15, and through the 90 felt pad 23.

On the forward end of the spring portion 27^a a resilient head 28, preferably made of rubber is adjustably mounted on the spring by means of a bolt 29. The rubber head 28 stands adjacent to the back of the target member 13 and between said target member, which is shown by dotted lines in Fig. 1, and the felt pad 23.

A part of the front face of the pad 23 100 may be cut away around the head 28 at 30 for the purpose of permitting the head 28 to have some rearward movement before it engages the felt pad.

Just above the spring 27 a clapper 31 is 105 pivotally supported. The clapper is so arranged as to normally drop by gravity to position just rearwardly of the upper end of the spring 27.

In the practical use of my improved 110 target the parts are installed, and the target is set up for use. When the target is shot

at with an air rifle and the marksman does not hit the bull's-eye, the shot will strike the felt pad 23 and either be embedded therein, or will drop to the bottom of the cylinder 10. If the bull's-eye is struck the shot will hit the rubber head 28, driving the spring portion 27^a and 27 rearwardly and cause the upper end of the spring 27 to strike the clapper 31 a sharp blow, whereby the clapper swings against the bell 25, the ringing of which indicates that the bull's-eye has been struck.

It will be noted that where the front part of the felt pad 23 is cut away at 30, as shown, or even in most cases where that is not done, if the felt is soft, the impact of the shot on the head 28 will drive the head rearwardly, so that during the first part of the movement of the head, there is little resistance to such rearward movement, while the farther the head moves rearwardly the greater becomes the resistance of the pad 23, so that the pad 23 reduces the strain and wear on the spring 27.

It will be noted that the members 20 with the flanges thereon serve the double purpose of supporting the partition 15 and supporting the target member 13.

It will readily be seen that my target is of comparatively simple and inexpensive construction and may be used for air rifle shooting and the like, and will save the shot so that the shot may be used again. Whenever the target member 13 has been mutilated to a certain extent, it may be removed and another similar member replaced.

It will be noted that the target is put together in such a way that it may be readily and easily taken apart for replacing or repairing the injured parts. A handle 31 may be secured to the rear upper part of the cylinder 10.

Some changes may be made in the construction and arrangement of the parts of my improved target without departing from its essential features and purposes, and it is my intention to cover by this application any such changes which may be included within the scope of my claims.

I claim as my invention—

1. A target comprising a hollow body with an inwardly extending flange at its forward end, said body having a slot adjacent to said flange, a perforable target member designed to be extended through said slot and mounted in said body, a solid partition mounted in said body rearwardly of the forward part thereof, a cushioning member mounted in front of said partition, a bell supported on said partition, a clapper pivotally mounted below said bell and adapted to normally hang downwardly, a spring supported on the rear surface of said partition, a forwardly extending member on said spring extended through said

partition and through said cushioning member, a head on the forward end of said forwardly extending member, said parts being so arranged that when said head is struck by a shot, the clapper will be agitated 70 to strike the bell, and the spring will return the head to its normal position.

2. A target comprising a hollow body with an inwardly extending flange at the forward end, said body having a slot adjacent to said flange, a perforable target member designed to be extended through said slot and mounted in said body, a solid partition mounted in said body rearwardly of the forward part thereof, a cushioning member mounted in front of said partition, a bell supported on said partition, a clapper pivotally mounted below said bell and adapted to normally hang downwardly, a spring supported on the rear surface of said partition, 80 a forwardly extending member on said spring extended through said partition and through said cushioning member, a head on the forward end of said forwardly extending member, said parts being so arranged 90 that when said head is struck by a shot, the clapper will be agitated to strike the bell, and the spring will return the head to its normal position, said cushioning member being of such thickness and resiliency as to 95 readily permit the first part of the movement of said spring, and also to receive the impact of the head and cushion it for reducing the final strain on the spring.

3. A target comprising a hollow body 100 with an inwardly extending flange at its forward end, said body having a slot adjacent to said flange, a perforable target member designed to be extended through said slot and mounted in said body, a solid partition, mounted in said body rearwardly of the forward part thereof, a cushioning member mounted in front of said partition, a bell supported on said partition, a clapper pivotally mounted below said bell and adapted to normally hang downwardly, a spring supported on the rear surface of 110 said partition, a forwardly extending member on said spring extended through said partition and through said cushioning member, a head on the forward end of said forwardly extending member, said parts being so arranged that when said head is struck by a shot, the clapper will be agitated to 120 strike the bell, and the spring will return the head to its normal position, a strip secured to said body on the interior thereof and having inwardly extending flanges adapted to be selectively secured to said partition and to support said perforated target member.

4. A target comprising a hollow body, a perforable target member removably mounted in the forward end thereof, a body of cushioning material spaced rearwardly from 130

said perforable member, a rigid member mounted rearwardly of said cushioning body, a head mounted between said perforable body and said body of cushioning material, said head being yieldingly supported on said rigid member, a bell suitably supported, a clapper pivotally mounted ad- jacent to the bell, said head and clapper and bell being so arranged that when said head is struck by shot, it will be driven rear- 10 wardly and the clapper will be agitated to strike the bell.

CHARLES H. WHITMAN.
